UNITED STATES PATENT OFFICE.

WALTER H. LENISH, OF CHICAGO, ILLINOIS.

ROLLER SCREEN.

Application filed November 22, 1926. Serial No. 149,849.

My invention relates to roller screen structure adapted particularly for installation in window frames.

Among the important objects of the invention are to provide improved structure in which the screen frictionally locks itself in any position to which it has been adjusted; to provide simple detachable lower rail structure for the screen material; and to provide improved track structure for frictionally receiving and guiding the rail bar.

The various features of my invention are incorporated in the structure shown on the drawings, in which:

15 Figure 1 is a front elevational view of a window frame showing a screen structure therein;

Fig. 2 is an enlarged sectional view on plane 2—2 of Figure 1;

20 Fig. 3 is a sectional view on plane 3—3 of Fig. 2;

Fig. 4 is an end view of the roller supporting box;

25 Fig. 5 is a sectional view on plane 5—5 of Fig. 2;

Fig. 6 is a sectional view on plane 6—6, Fig. 3; and

30 Fig. 7 is a sectional view on plane 7—7, Fig. 3, but showing a modified construction.

35 On Figure 1, F represents a window frame to which I have shown my improved roller screen applied. The screen fabric S is mounted on a roller 1 enclosed within a housing or box structure B. This box

40 may be of any desired shape, but I have shown it of rectangular cross section, constructed of sheet metal. The box body is formed from a single piece of sheet metal with its ends deflected downwardly to form

45 guide lips 2 and 3 for the outlet opening 4 for the screen material. The closure cap structures 5 and 6 for the box body are deflected outwardly and inwardly along their periphery to form the double flanges or

50 sockets 7 and 8 for receiving the respective ends of the box body, this making a very good joint between the caps and the body and also making the box stiff and rigid at its ends. To further strengthen the caps, they

55 may have concentric corrugations 9.

The roller 1 is of sheet metal bent to tubular form and having its ends 10 and 11 deflected radially inwardly to leave a slit 12 into which the upper edge of the screen fabric may be inserted and secured. The roller tube has the end bushings 13 and 14

which receive the shaft 15. At its ends the shaft extends through the openings 16 and 17 in the respective end caps 5 and 6. At one end a nut 18 threads onto the shaft outside of the cap and at the other end a key 19 is inserted through the shaft outside of the cap, the nut and key holding the shaft in proper axial alignment. Within the tube 1 is the torsion spring 20 which encircles the shaft and has its one end 21 abutting against the tongue or lip 11 of the roller tube, while its other end 22 is secured in the slot 23 extending inwardly from the adjacent end of the shaft. The spring is thus anchored at 70 one end to the shaft and at its other end to the roller tube. The shaft is normally locked against rotation by the arm 19' extending from the key 19 and engaging at its outer end in the slot 24 cut in the flange of 75 the end cap 6.

The screen fabric is secured at its upper edge in the slit 12 and is wound around the roller (clockwise direction, Fig. 2) its outer end passing through the outlet 4 and downwardly between the lips 2 and 3 of the box B. Downward pull on the screen fabric will rotate the roller tube, such rotation being communicated by the tongue 11 of the roller tube to the end 21 of the spring, and the spring is therefore wound up and resists such rotation of the roller tube by pulling of the fabric. As the spring is wound up, it tends to contract axially but this can readily happen as the spring end 21 may 90 slide along the abutment tongue 11.

The screen containing box may be built into the window frame structure or, as shown in Fig. 1, the box may be detachably applied at the upper end of the window frame opening just in front of the plane of movement of the window sash so as not to interfere with the opening and closing of such sash. To accommodate the cap ends of the box and to permit the screen fabric to extend the full width between the jambs of the window frame, the jambs have the recesses 25 cut therein into which the box ends extend and on the lower wall of which they rest to support the box, flanges 26 extending downwardly from the caps being secured, as by screws, against the inner faces of the jambs to thus securely lock the box in position. Secured to each jamb are front and rear guide strips 27 and 28 forming between them channels 29 for receiving the side edges of the fabric and the ends of the

rail bar structure R to which the lower end of the screen fabric is secured. The structure and arrangement of the guide strips is clearly shown in Fig. 6. Each guide strip 6 is of L shape and the strips are secured with their base sections 30 against the jamb as by means of screws 31, the limbs of the strips extending parallelly and having their outer ends 27' and 28' respectively deflected toward each other to leave the narrow entrance slot 32 to the channel 29. The guide strips are so located on the jambs that the channels 29 will be in register with and open into the passageway or mouth 4 of the roller box 10. The strips on each jamb are strengthened and seated between inner and outer stop strips or mouldings 33 and 34, detachably secured to the jambs, the outer strips forming the inner stops for the lower window 15 sash. As will be explained later, the ends of the rail bar R project into the channels 29 and have frictional engagement with the guide strips, and to make the guide strips more flexible, the outer walls 35 are formed 20 thereon along the outer ends 27' and 28' and a distance inwardly along the limbs 27 and 28 and separated a distance from the limbs. The guide strips are preferably of spring metal and the double wall structure can be 25 readily formed on a single strip of metal by means of proper dies. The stop mouldings 33 and 34 will be applied to engage against the outer walls 35 of the strips thus leaving the inner walls 27 and 28 free to readily 30 flex during their frictional engagement with the rail bar F. By means of the double wall construction on the guide clips, the edges 32' are round and smooth so as to prevent injury to the screen fabric. 35

Describing now the rail bar structure, it comprises the two clamping strips 36 and 37 of sheet metal and having the strengthening and stiffening ribs 38 adjacent to their longitudinal edges. These strips receive between them the lower end of the screen fabric and are secured together by bolts 39 to clamp the fabric. 40

Preferably a rubber strip 40 is interposed between the fabric and the inner strip 37 45 to increase the frictional engagement of the strip with the fabric, and at the lower edge of the rubber strip is formed the sealing shoe or bead 41 for engaging against the window sill when the screen fabric is pulled down. 50

At each end of the rail bar structure, plates 42 and 43 are interposed between the strips 36 and 37 and at opposite sides of the screen fabric. At their outer ends, the plates are deflected to form the parallel and opposed friction walls 44 and 45 for engaging against the walls 27 and 28 of the guide strips, the plates being of spring metal. The plates may be longitudinally adjusted so as to properly position their friction walls 55

in the channels 29. As shown, the plates have the slots 46 through which the bolt 39 extend which clamp the outer ends of the rail bar strips 36 and 37 together. The slots 46 permit longitudinal adjustment of the plates. The bolts 39 may serve also to secure small handles 47 to the rail bar structure so that the screen may be more readily raised and lowered. 60

When a roller screen structure is installed 75 on a window, the box B is secured to the top of the frame, as has been described, and the outer guide strips 28 are first applied. Then the rail bar ends are brought into position and the inner guide strips 27 secured 80 to form the channels 29, and then the inner stop strips 33 are applied. The frictional engagement of the rail bar friction walls with the guide strips and the tension of the spring 20 are such that the screen may be 85 readily raised or lowered by means of its handles 47 and will remain in the position to which it has been placed, the spring tension being just sufficient to take up the slack at all times. 90

The width of the slot 32 leading to the channel 29 is just sufficient to permit the plates 42, 43 to travel easily therein and to prevent passage of insects between the screen fabric and the outer edges of the guide strips above the rail bar. The guide strips may be of sufficient lateral extension so that the screen fabric will extend at its sides a sufficient distance into the channels 29 to prevent accidental withdrawal of the fabric from the channels during operation and service of the screen. Grooves 49 may be cut in the jambs in alignment with the channels 29 so as to afford ample clearance space for the rail bar friction walls 44, 45 and for the screen material during transverse shift of the screen, or where there are irregularities in the width of the window frames. Scraping or binding of the rail bar structure and screen will 100 therefore be prevented. 110

When the screen is drawn all the way down, the shoe 41 along the lower edge of the rubber insert strip 40 will bear against the sill and will seal the window opening 115 against the passage of insects. The width of the rail bar structure is also such that when the screen is entirely raised the upper edge of the rail bar will extend into the passageway 4 between the lips 2 and 3 120 of the roll box, and the upper ribs 38 of the rail bar structure will abut against the lower edges of the lips so that the rail bar structure will form a closure for the passageway 4 to thus seal and protect the 125 screen fabric within the box B. The front lip 3 is preferably inclined, as shown, so as to prevent rubbing of the screen material over a sharp edge as it is wound upon the roller and its diameter increases. The 130

lower edges of the lips 2 and 3 are also preferably turned back, as indicated, to form well rounded edges on which the screen fabric will travel.

- 5 In order to prevent accidental opening of the screen when it has been brought down against the window sill, locking means are preferably provided. As shown, the guide strips 27 and 28 are deflected inwardly to 10 form humps or projections 50 and the friction walls 44 and 45 of the rail bar structure are deflected to form depressions or pockets 51 for receiving the humps 50 when the screen is entirely down, such 15 spring and friction engagement serving to hold the screen in its lower position but not interfering with raising of the screen when desirable.

The side edges of the screen fabric are 20 preferably selvedged and strengthened. Such strengthening may be accomplished by weaving a stranded wire cord 52 into the selvedge edges. This will strengthen the fabric and prevent distortion thereof particularly along the edges. Such strengthening will, however, increase the thickness of the fabric at the edges, and to allow for this and to insure uniform wind-up of the fabric on the rollers, the roller ends are 25 reduced in diameter. As shown, the bushings 13 and 14 are reduced in diameter at their outer projecting ends and thin sheet metal ferrules 53 are applied around the bushings and the ends of the roller tube 1 30 to form a continuation of said tube of reduced diameter. The selvedge or strengthened edges of the fabric will wind up along the reduced end sections and the fabric roll will always be in uniform diameter and 35 the fabric will not stretch unevenly and become distorted. The ferrules 53 may also serve to hold the roller tube in proper shape, such tube being formed partly open by means of dies and then contracted, but the 40 ferrules when slipped over the ends will hold the roller tube to its proper cylindrical 45 shape.

The key 19 which normally holds the shaft 15 against rotation may be readily 50 released to permit rotation of the shaft to adjust the spring tension. The arm 19' of the key normally extends into the slot 24 to lock the key in place, as has already been explained. To release the key, its arm 19' 55 is first swung a distance around the shaft axis to release the arm from the slot 24, and then the arm may be swung in axial direction clear of the slot 24 and the adjacent cap flange 8. When the spring is to be adjusted, the rail bar is first raised its entire 60 distance to engage in the passageway 4, and then the key is released. At the other end of the shaft is a screw-driver slot 54 which normally is surrounded by the nut 18. After release of the key 19, a screw

driver may be inserted in the slot 54 and the shaft readily turned to adjust the tension of the spring, and then the key is again locked by inserting the end of its arm 19' into the nut 24. The nut which surrounds 70 the slot 54 will securely keep the screwdriver in the slot and will prevent its slipping out of the slot during the adjustment operation of the spring.

In Fig. 7 is shown a modified form of 75 guide strips adaptable where plaster jambs are associated with the window opening. With such an arrangement wooden strips 55 may be embedded in the plaster jambs 56 and separated by a channel 57. The 80 guide strips used with this arrangement are generally L shaped with their inner walls 58 engaging the opposed faces of the strips 55 and forming a lining for the channel 57, and their outer limbs 59 extending over the 85 inner side faces of the wooden strips 55. At their angles, the strips are deflected to form the diagonal projections 60 which form the slots 61 for receiving the guide plates 42 and 43 at the respective ends of the rail 90 bar structure. The friction walls 44 and 45 at the ends of the plates engage against the walls 58 of the guide strips in the channel 57. The ribs or beads 62 along the outer edges of the guide strips increase the 95 strength and stiffness of the strips and also form bridges to cover the joints between the wood strips and the adjacent plaster jambs 56.

The rubber strip 40 in the rail bar structure is preferably projected a distance above the inner clamping strip 37 to form a cushion for the screen fabric when the fabric passes around the edge of the inner lip 2 when the rail bar structure reaches its upper 100 position and enters the passageway 4. Such cushioning will prevent abrupt bending and cracking of the screen fabric. This provides a simple and efficient roller screen 105 structure which can be readily installed, operated, and kept in adjustment. On account of the open or separated guide strips and the separated friction walls which permit unhindered lateral extension of the 110 screen fabric, there will be plenty of clearance space to take care of irregular widths of the screen fabric and thickness at the selvedge edges, and irregularity of the width between the jambs of the window frame. The reduced diameter at the ends of the 115 roller tube permits the selvedged and reinforced screen material to become uniformly rolled up on the roller and stretching and distortion of the fabric will be prevented. The friction engagement of the friction 120 walls with the guide strips will hold the screen in any adjusted position and the friction projections and pockets will lock the screen in closed position against any accidental opening thereof. The roller spring 125

- is not depended upon to move the screen to any position, the tension of the spring being sufficient to at all times keep the slack out of the screen and to keep it properly 40
5 stretched between the rail bar and the roller. When the screen is entirely up, the rail bar engages in the mouth of the box and entirely seals the box so that the rolled-up screen will be fully protected against the weather and 45
10 the entrance of insects, dirt, etc.
- The outlet slot from the roller box is so located that the screen will be given plenty of clearance and drag thereon will be prevented particularly when it is under tension. 50
15 The guide strips also afford ample clearance so that friction and wear are reduced to a minimum. 55
20 The separate front and rear guide strip construction permits installation or removal 60
25 of the strips without removing the roller box from its position.
- As there may be more or less lateral shift of the screen during operation thereof, the latch pockets or notches 51 in the friction 65
25 walls of the rail bar structure are elongated laterally so that proper latching cooperation with the projections 50 will be at all times assured, when the screen is in closed position. 70
Having described my invention, I claim as 75
30 follows:—
1. In a roller screen structure, the combination of a roller, screen fabric mounted on said roller, a guide rail structure at the outer end of said fabric, said guide rail comprising opposed clamping strips receiving the fabric between them and terminating short of the outer edges of said fabric, spring plates extending from each end of said guide rail and at opposite sides of the 80
35
- projecting fabric, and guide strips forming channels for receiving said spring plates, said spring plates having frictional engagement with said guide strips for securing the fabric in adjusted position. 85
2. In a roller screen structure, the combination of a roller, screen fabric mounted on said roller, a rail bar structure comprising opposed sheet metal strips detachably secured together and clamping between them the outer end of said fabric, guide plates at 90
95 the ends of said rail bar structure and clamped between the ends of said sheet metal strips on opposite sides of said fabric, the outer ends of said plates being separated from each other and from said fabric, and guide strips forming guide channels for receiving the ends of the guide plate, the frictional engagement of said guide plates with said guide strips locking said screen in adjusted position. 100
3. In a roller screen structure, the combination of a roller, screen fabric mounted on said roller, a guide rail structure at the outer end of said fabric, said guide rail comprising opposed clamping strips receiving the fabric between them, spring plates extending from each end of said guide rail at opposite sides of said fabric, guide strips forming channels for receiving said spring plates, said spring plates having frictional engagement with said guide strips for securing the fabric in adjusted position, and means for adjusting said plates longitudinally relative to said guide rail. 105
In witness whereof, I hereunto subscribe my name this 4th day of November, 1926. 110
WALTER H. LENISH.
